UNITED STATES PATENT OFFICE.

HARRY L. SHULMAN, OF NEW YORK, N. Y., ASSIGNOR TO LEVY SHULMAN & COMPANY, INC., OF NEW YORK, N. Y., A CORPORATION OF NEW YORK.

SHIPPING BOX.

Application filed April 13, 1923. Serial No. 631,847.

To all whom it may concern:

Be it known that I, HARRY L. SHULMAN, a citizen of the United States, residing at New York, N. Y., have invented certain new and useful Improvements in Shipping Boxes, of which the following is a specification.

In the shipment or transportation of certain classes of merchandise, particularly clothing or wearing apparel, it is the common practice to use paper, card or fiber board boxes to contain the goods. These boxes are often shipped express or shipped without being sealed; a cord or string being sometimes passed around the boxes and tied to hold the boxes in closed position. It frequently happens that the lids of these boxes are raised while in transit and the hands of unauthorized persons inserted and the contents removed; the lids then being closed and the boxes to all outward appearances being intact and in full possession of their contents.

It is the primary object of the present invention to provide means whereby the now commonly used shipping boxes of this character may be made more difficult of access to the interiors thereof, whereby to reduce to a great extent the obnoxious practice mentioned, and to render it practically impossible to handle or remove the contents of the boxes without leaving outward signs or indications of such acts.

The invention aims further to provide means of an extremely simple nature for the accomplishment of these ends, and whereby the shipping packages constructed in accordance with the invention are rendered less liable to crushing or breaking as a result of rough handling in shipment.

A still further object of the invention is to provide means whereby the contents of the box may be easily and quickly sealed against unauthorized inspection or handling, and which acts to prevent dirt or dust gaining access to the contents of the box.

With these objects in view, together with others which will appear as the description proceeds, the invention consists in the novel construction, combination and arrangement of parts, all as will be described more fully hereinafter, illustrated in the accompanying drawings, and particularly pointed out in the claim.

In the drawings:

Fig. 1 is a perspective view of a conventional type of shipping box for clothing, equipped in accordance with my invention, and showing the outward appearance of the same when packed and ready for shipment, 55

Fig. 2 is a similar view with the lid of the box removed.

Fig. 3 is an enlarged longitudinal sectional view taken through the box as shown in Fig. 1, and

Fig. 4 is a transverse sectional view taken through the improved shipping box.

The box shown in the present illustration as constructed in accordance with the invention is one of familiar construction; being of rectangular shape and comparatively shallow, providing a bottom 5, end walls 6, side walls 7, and a removable top or cover 8. The cover may be either hingedly connected at one edge to the tray portion of the box, or may be entirely removable therefrom, as shown in the present illustration. However, the particular form of box or cover arrangement forms no part of the present invention.

It is proposed, in connection with boxes of this general character, to provide flaps, wings or cover plates to overlie the contents of the tray portion of the box, and these wings or flaps wholly protect the box contents and are to be securely sealed over the same. The material of which these wings or flaps are made may be the same as used in the construction of the box itself.

The wings, in the present instance, are of 90 relatively heavy card or fiber board, and one wing is attached to each side wall of the box tray; being of equal length with the box. Each wing has at one edge thereof an attaching means in the form of a supplemental 95 or reinforcing wall 9, equal in length and depth with the side walls of the box tray. These supplemental wall portions are secured to the inner faces of the sides 7 of the tray by the securing staples or clips 10 and 100 the wing portions or members 11 connect with these supplemental walls in the plane of the upper edges of the box tray sides and ends. The wing members are adapted in use to lie flush with the upper edges of the 105 box tray parallel with the bottom 5 of the box and hingedly connect with their respective walls. Each wing, as before stated, is

of substantially the same length as the box tray, and each is of a breadth slightly greater than one half the breadth of the tray, whereby the wings will cover the contents of the tray in overlapping relation.

The ends of the box tray and the uppermost of the wing members are provided with sealing flaps in the form of adhesive strips 12. The strips on the ends of the tray have their free edges extending slightly above the tray edge, so that they may be turned down upon the next adjacent portions of the horizontally disposed flaps or wings 11, while the adhesive strip carried by the uppermost wing 11 projects beyond the free edge thereof to overlie and adhere to the opposing wing 11. The sealing strips 12 on the tray ends may be of equal length with the breadth of the box, so as to entirely close the seam between the wing edges and the edges of the box, or they may be of less length, as desired.

From this construction, it is apparent that when the box is filled and the wings folded inwardly into parallelism with the box bottom and sealed with the strips 12, as described, the contents will be securely held in the tray and closed to inspection. This sealing arrangement also prevents dust or dirt gaining access to the interior of the box tray. When numbers of these filled boxes are piled upon each other, the supplemental wall portions 9 will assume their proportionate share of the weight of the overlying boxes and thus prevent crushing of the box sides.

Should the lids or covers of the boxes thus sealed be lifted or removed and the hands of unauthorized persons inserted to handle or remove the box contents, the sealed wings will obstruct such operation and prevent such operations unless the seals are broken and the wings lifted. This cannot be done readily without removing or upsetting the overlying boxes of the pile; thus making the act so tedious and cumbersome as to discourage theft.

The wing members and their attached supplemental sides are constructed with a view to their ready application to boxes now in use, so that specially constructed box trays, for the accomplishment of the purposes stated, need not be resorted to.

I claim:

In a device of the class described, a box tray having the usual upstanding side and end walls, a pair of supplemental cover members, a wall portion hingedly carried by each member, the said wall portions being of equal breadth and length with the side walls of the tray, means for securing the said wall portions to the said side walls of the tray, the said cover members adapted to overlap each other when lowered and to cover the tray, adhesive members connecting the free ends of the cover members and with the end walls of the tray, and a main cover to telescope over the said tray.

In testimony whereof I affix my signature.

HARRY L. SHULMAN.
